UNITED STATES PATENT OFFICE.

HENRY C. HUNT, OF PALACIOS, TEXAS.

TOOL FOR REMOVING FLOORS, SIDING, SCAFFOLDS, &c.

1,030,660.

Specification of Letters Patent. Patented June 25, 1912.

Application filed October 12, 1911. Serial No. 954,387.

To all whom it may concern:

Be it known that I, HENRY C. HUNT, a citizen of the United States, residing at Palacios, in the county of Matagorda and State of Texas, have invented a new and useful Tool for Removing Floors, Siding, Scaffolds, &c., of which the following is a specification.

The invention relates to improvements in tools for removing floors, sidings, and for taking down scaffolding, etc.

The object of the present invention is to improve the construction of tools, and to provide a simple, efficient and comparatively inexpensive device of great strength and durability, adapted to save material and labor in taking down houses, scaffolding, fencing and the like and opening boxes and capable of performing similar operations and of readily separating any two pieces of nailed lumber without scarring or otherwise damaging the same.

With these and other objects in view, the invention consists in the construction and novel combination of parts hereinafter fully described, illustrated in the accompanying drawings, and pointed out in the claims hereto appended; it being understood that various changes in the form, proportion, size, and minor details of construction, within the scope of the claims, may be resorted to without departing from the spirit or sacrificing any of the advantages of the invention.

In the drawings:—Figure 1 is a perspective view of a tool, constructed in accordance with this invention. Fig. 2 is an enlarged longitudinal sectional view of one end of the tool. Fig. 3 is a plan view of the same. Fig. 4 is a transverse sectional view on the line 4—4 of Fig. 2. Fig. 5 is a perspective view, the tool being arranged for taking up flooring. Fig. 6 is an elevation partly in section, the tool being arranged for removing siding from the interior. Fig. 7 is a perspective view, the tool being arranged for taking down scaffolding. Fig. 8 is a perspective view, the tool being in position for removing the casing of a window.

Like numerals of reference designate corresponding parts in all the figures of the drawings.

In the accompanying drawings in which is illustrated the preferred embodiment of the invention, the tool, which is designed to

be constructed of tool steel and to be made in various sizes to suit the character of the work to be performed, consists of a straight bar or body portion 1, provided at one end with a claw 2 and having a short inclined or angularly disposed neck or portion 3, extending downwardly from its other end and arranged at an obtuse angle to the straight bar or body portion and formed integral with the same and with a straight shank 4. The shank 4, which extends outwardly from the outer end of the inclined portion or neck, is off-set from the plane of the straight bar or body portion 1 by the said neck or portion 3, and has its bottom face 5 arranged in a plane in approximate parallelism with the plane of the straight bar or body portion, and it is centrally connected with an integral cross head 6, extending laterally from opposite sides of the shank 4 and forming laterally projecting arms, which space tapered or wedge-shaped fingers or bills 7 from each other. A nail extracting claw 8 extends inwardly from the inner end of the shank 4 and is off-set from the straight bar or body portion 1 by the inclined or angularly disposed neck to provide a space for the hand of the operator in pulling a nail. The claw 8 has a flat bottom or outer face in flush relation with and forming a continuation of the bottom face 5 of the shank 4. The bottom face 9 of the cross head 6 is in flush relation with the bottom face 5 of the shank 4, and the shank and the cross head form a T-shaped head or portion, which may be conveniently used as a backing in driving nails. The tapered or wedge-shaped bills or fingers are located at the front or outer face of the cross head 6 and at the ends thereof, and they extend upwardly from a point below the plane of the straight bar or body to a point above the same, and they are arranged approximately at right angles to the said bar or body portion. The bills or fingers 7 have flat inner or rear faces and inclined or angularly disposed front faces, and they are rounded at the bottom at 10 to form a fulcrum for the tool when the claw 8 is used for extracting a nail. By extending the fingers or bills upward from the ends of the cross head across the plane of the straight bar or handle from a point below the same, they form laterally off-set fulcrums arranged in the plane of the bar 110

or handle, and when one of them is used as a fulcrum, and the other for engaging a board, there will be no liability of the tool turning in the hand of the operator.

5 In Fig. 5 of the drawings the tool is shown arranged for taking up flooring 11. The cross head is placed upon the joists 12 and the bills straddle the latter and hook under the flooring. The cross head forms 10 a fulcrum and the bills or fingers pull upward and outward, drawing the nail in the direction in which it is driven, and at the same time lifting or separating the tongue and groove without damage.

15 In Fig. 6 is illustrated the manner of taking down siding 13 from the inside of a house without a scaffold. Beginning at the top one board is taken off at a time, leaving the next board free at the upper edge and the 20 boards are removed without damaging them. One of the bills or hooks is inserted into the space between the inclined side and the studding 14, and the other bill or hook bears against one of the boards, as clearly shown 25 in Fig. 6. By drawing downward on the straight bar or handle portion, the board is separated from the studding, and owing to the fingers or bills extending into the plane of the straight bar or handle, the weight, 30 the fulcrum and the power are in a line which prevents any twisting of the tool.

In Fig. 8 the tool is shown arranged for removing the casing 15 from a window frame, the portions or bills being introduced 35 between the casing 15 and the jamb or supporting frame-work 16. In this position leverage may be applied by moving the straight bar or handle portion upward or downward, as may suit the convenience of 40 the workmen.

In Fig. 7 the tool is arranged for taking down a scaffold, the bills being engaged, respectively, with an upright 17 and a horizontal timber 18, and is adapted to be swung 45 horizontally to separate two pieces of lumber.

It will be seen that the tool is particularly adapted for carpenters and others where it is desired to separate two pieces of timber 50 nailed together, and it is adapted for taking down houses, fencing and various other

structures without scarring or damaging the material.

The tool may be used for stretching wire and various other work where a floor bar is 55 of advantage.

What is claimed is:—

1. A tool of the class described including a straight bar or body portion provided at one end with a downwardly inclined or 60 angularly disposed neck, a short shank extending outwardly from the outer end of the neck in a plane approximately parallel with that of the straight bar or body portion, a cross head or bar centrally connected 65 to the outer end of the shank and extending from opposite sides of the same to form laterally projecting arms, and bills or fingers located at the ends of the cross head or bar and extending upwardly therefrom at a 70 point below the plane of the straight bar or body portion at right angles thereto and forming laterally off-set fulcrums arranged in the plane of the straight bar or body portion.

2. A tool of the class described including a straight bar or body portion provided at one end with a downwardly inclined or angularly disposed neck, a short shank extending outwardly from the outer end of the 80 neck in a plane approximately parallel with that of the straight bar or body portion, a cross head or bar centrally connected to the outer end of the shank and extending from opposite sides thereof to form laterally projecting arms, a nail extracting claw extending inwardly from the outer end of the neck and off-set by the same from the bar or body portion, and bills or fingers located at the ends of the cross head and extending 90 upwardly therefrom at a point below the plane of the straight bar or body portion and forming laterally off-set fulcrums in the plane of the said bar or body portion.

In testimony, that I claim the foregoing 95 as my own, I have hereto affixed my signature in the presence of two witnesses.

HENRY C. HUNT.
